[57] CLAIM

The ornamental design for the front bezel with an adapter panel, as shown and described.

DESCRIPTION

FIG. 1 is a reduced top front and right side perspective view of a front bezel with an adapter panel;

FIG. 2 is a front view;

FIG. 3 is a top view;

FIG. 4 is a bottom view;

FIG. 5 is a left view; and,

FIG. 6 is a right view.

The broken lines of FIG. 1 are for illustrative purposes only and form no part of the claimed design.

The areas identified by the pattern in FIGS. 1 and 2 represent the color black.
